Primary Examiner — Clare E Heflin(74) *Attorney, Agent, or Firm* — HYIP(57) **CLAIM**

The ornamental design for a high bay light, as shown and described.

DESCRIPTION

FIG. 1 is a first perspective view of a high bay light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion, in FIG. 1.

The broken lines shown in the drawings depict portions of the high bay light in which the design is embodied that form no part of the claimed design.
